UNITED STATES PATENT OFFICE.

EPHRAIM B. COBAUGH, OF MIDDLETOWN, PENNSYLVANIA.

COMBINED BRACE AND RACK FOR TENTS.

SPECIFICATION forming part of Letters Patent No. 761,582, dated May 31, 1904.

Application filed December 31, 1902. Serial No. 137,327. (No model.)

To all whom it may concern:

Be it known that I, EPHRAIM B. COBAUGH, a citizen of the United States, residing at Middletown, in the county of Dauphin and State 5 of Pennsylvania, have invented new and useful Improvements in Tents, of which the following is a specification.

My invention relates to new and useful improvements in combined braces and racks for 10 tents; and its object is to provide a brace which may be detachably secured to the uprights or supports of a tent and which is provided with suitable means whereby clothing, firearms, and other articles may be readily 15 suspended therefrom.

With the above and other objects in view the invention consists in the novel construction and combination of parts hereinafter more 20 fully described and claimed, and illustrated in the accompanying drawings, showing the preferred form of my invention, and in which—

Figure 1 is a perspective view of the standards and cross-bar of a tent and showing my improved brace-bar in position thereon, the 25 position of the tent in relation to the supports, &c., being disclosed in dotted lines.

Fig. 2 is a detail view of the upper portion of 30 one of the supports and showing the adjacent ends of the cross-bar and brace-rod detached.

Fig. 3 is a perspective view of a portion of the brace-bar shown in inverted position.

Referring to the figures by numerals of reference, 1 1 are uprights of a tent, to the upper end of one of which is hinged a cross-bar 35 2, having a tongue 3 at each end adapted to rest within grooves 4, formed in the upper ends of the uprights 1. These uprights and the cross-bar are adapted to support a tent of any suitable form, and the uprights are braced 40 in vertical position by means of a rod 5.

Dovetails 6 are preferably formed at the ends of this rod, and each is adapted to be seated in a tapered groove 7, V-shaped in cross-section and formed within a casting 8, secured 45 to the inner face of standard 1. It will be

understood that when the ends of the brace-rod are placed within these grooves 7 and drawn downward thereinto the two uprights 1 will be firmly secured together and braced.

A series of hooks 9 are secured to one or 50 both of the sides of brace-bar 5, and bolts 10 are preferably arranged vertically within said rods at desired intervals. Upon these bolts are pivotally mounted strips 11, each of which is in the form of a double bow. These strips 55 are normally arranged under and in alinement with the rod 5; but they can be readily swung laterally therefrom and form racks upon which may be placed rifles, fishing-rods, &c. Clothing, baskets, and other similar articles 60 may be suspended from the hooks 9, before referred to.

In the foregoing description I have shown the preferred form of my invention; but I do not limit myself thereto, as I am aware that 65 modifications may be made therein without departing from the spirit or sacrificing any of the advantages thereof, and I therefore reserve the right to make such changes as fairly fall within the scope of my invention. 70

Having thus described the invention, what is claimed as new is—

The combination with the standards of a tent and a cross-bar detachably connecting the same; of a holding device upon each standard and having a tapered dovetail groove therein, a brace-rod arranged between the standards, dovetails integral therewith and adapted to be seated within the grooved holding devices, a strip centrally pivoted to the brace-rod and having its ends upwardly curved to 75 form brackets, said ends being adapted to be swung at angles to the brace-rods, and hooks extending from the rod. 80

In testimony whereof I affix my signature in 85 presence of two witnesses.

EPHRAIM B. COBAUGH.

Witnesses:

JOHN B. LINGLE,
CATHARINE FARRINGTON.
